UNITED STATES PATENT OFFICE.

ELKANNAH S. PERRY, OF NEWARK, OHIO.

PERMUTATION-LOCK.

1,294,943.

Specification of Letters Patent. Patented Feb. 18, 1919.

Application filed June 1, 1918. Serial No. 237,778.

To all whom it may concern:

Be it known that I, ELKANNAH S. PERRY, a citizen of the United States, residing at Newark, in the county of Licking and State of Ohio, have invented certain new and useful Improvements in Permutation- Locks; and I do declare the following to be a full, clear, and exact description of the invention, such as will enable others skilled in the art 10 to which it appertains to make and use the same.

My invention relates to permutation locks and more particularly to pad locks, although the bolt retracting means constituting the 15 principal novelty of the invention, is equally well adaptable to numerous other kinds of locks.

One object of the invention is to provide for easy assembling and disassembling of 20 the lock.

A further object is to provide a novel operating disk which must be turned to and fro in a predetermined manner to release the lock.

With the foregoing objects in view, the 25 invention resides in the novel features of construction and unique combinations of parts to be hereinafter fully described and claimed, the descriptive matter being supplemented by the accompanying drawings which form a part of this specification and in which:

Figure 1 is a sectional view illustrating the first step in opening the lock;

Fig. 2 discloses the second position of parts;

Fig. 3 illustrates the third step in releasing the lock;

Fig. 4 discloses the locking bolt completely released;

Fig. 5 is a horizontal section on the plane indicated by the line 5-5 of Fig. 4;

Figs. 6 and 7 are detail vertical sections through the operating disk.

In the drawings above briefly described, the 45 numeral 1 designates a suitably shaped casing having a shackle 2 with one end 3 slidably and rotatably mounted in the casing and provided with a coiled spring 4 which tends to project the shackle to released position the moment the locking bolt is retracted. The other end of the shackle 2 projects normally through an opening 5 in the edge of the casing 1 and retains a pivoted latch member 6 in operative position as seen most

clearly in Fig. 5, said latch being received in a notch 7 or other suitable keeper with which the removable side plate 8 of casing 1 is provided. This plate is preferably held in place by pins 9 and bayonet slots 10 and must therefore be rotated a slight distance before it can be removed. This rotation however is prevented by the latch 6 until the lock is released and the shackle opened. When this is done, a small instrument may be inserted in the opening 5 to release the latch 6, whereupon plate 8 may be turned to the required extent and then entirely detached, thus giving access to the 60 interior of the lock.

To retain the shackle 2 in operative or locked position, a sliding bolt 11 is mounted in the casing 1, preferably at the upper end of the latter, the free end of said bolt being receivable in a notch 12 in the shackle. Bolt 70 11 is provided with an inwardly extending lug 13 with which the upper end of an operating lever 14 co-operates, said lever being fulcrumed to a suitable arm 15 depending from a plate 15^a upon the lower side of 75 which the bolt 11 is mounted, said plate being secured to the upper end of the casing 1, the edge of said plate opposite arm 15 having a depending flange 15^b between which and said arm, the bolt slides. For a 80 purpose to hereinafter appear, it is desirable that the lever 14 shall be normally forced in one direction by spring tension, and as it is also desirable to project the bolt 11 by 85 spring action, I preferably provide a double acting spring 16 connected operatively to both said lever and bolt to act upon them in the required manner.

The end of the lever 14 remote from the lug 13 is provided with a laterally extending finger or shoe 17 receivable in grooves formed in one face of an operating disk 18 located in the casing 1. Disk 18 is shown as provided with three grooves 19, 20 and 21, and with a master way 22 extending 95 from the center of the disk to its edge. One end of groove 19 communicates with the master way 22 and the other end of said groove opens at 19^a into the groove 20, the latter being at this point slightly greater in 100 depth than the groove 19. The end of groove 20 adjacent the point 19^a, communicates with the master way 22, while the other end of said groove 20 opens at 20^a into the third groove 21, the latter at the 105 110

point 20^a, being of greater depth than groove 20. Adjacent the point 20^a, the groove 21 opens into the master way 22 and at 21^a the other end of groove 21 bulges abruptly outward and communicates also with the master way 22.

With the disk 18 standing as seen in Fig. 1 the shackle 2 is locked in closed position and the shoe 17 is located at the entrance to 10 the groove 19. The disk is now turned a predetermined amount so that shoe 17 is guided into groove 20 as seen in Fig. 2, and it will be observed that if the disk is turned a fraction of an inch too far, the shoe will be disposed in the master way 22, whereupon 15 the spring 16 will return the lever 14 to its initial position. From the position of Fig. 2 the disk 18 is turned in the opposite direction so that shoe 17 travels around groove 20 and enters groove 21 as seen in Fig. 3. 20 Here again, if the disk is turned to an excessive extent, the shoe will leave groove 21 and enter the master way 22, in which it will return to its initial position. From the position 25 illustrated in Fig. 3 the disk 18 is again turned in the direction in which it was first rotated, whereby to cause shoe 17 to travel around groove 21, the bulge 21^a of the latter serving to impart the final movement 30 to lever 14 which retracts the bolt 11 (see Fig. 4). When this takes place, the spring 4 forces the shackle 2 outwardly to permit 35 it to be swung aside. By now turning the disk 18 a fraction of a revolution, lever 14 will return to its initial position, due to reception of shoe 17 in the master way 22, and 40 spring 16 will exert a constant stress on the bolt 11, such stress serving to project the bolt into the notch 12, the moment the shackle is again forced home.

By means of a central stub shaft 23 and a nut 24, the disk 18 is secured frictionally against one side of a second and larger disk 25, the latter being rotatably mounted on the 45 shaft 23 and having an operating knob 26 located on the exterior of the casing. By turning this knob to and fro in the predetermined manner, the lock may be released as above described, and in order that the device 50 may be operated successfully either in daylight or dark, the disk 25 is provided with a plurality of relatively large notches 27 and with a series of smaller notches 28, all of which coöperate with a spring 55 "click" 29. When employing the combination shown, the knob 26 is rotated clockwise until the operator feels and hears the click 29 travel over the series of notches 28 and into the first relatively large notch 27. By 60 turning knob 26 and counting five "clicks," the parts are located as in Fig. 2. Rotation of the knob in the opposite direction for five "clicks" will locate the parts as seen in Fig.

3, and movement of said knob for six "clicks" in the direction in which it was first 65 turned, will now release the lock as seen in Fig. 4. A slight counter clockwise turn is now all that is necessary to again set the lock so that it will snap to locked position when the shackle is forced in.

By securing the disk 18 against the disk 25 in the manner shown and described, or in any other equivalent manner, it will be obvious that the two may be relatively adjusted in such a manner as to vary the starting point of the combination in a great number of ways; and particular emphasis is laid upon the fact that no change in combination necessitates a change in the construction on the disk 18.

Particular attention is directed to the fact that the grooves in the disk 18 are in the side thereof facing the side of the casing which is open before application of the plate 8, and to the carrying of the bolt 85 11, the lever 14 and spring 16 by the plate 15^a. By these features, after the disk has been mounted in the casing, the aforesaid bolt, lever, spring and plate are inserted as a unit into the casing through its open side, 90 the shoe 17 being then receivable in one of the cam grooves or in the masterway 22 of the disk. A single screw is all that is required to secure the plate 15^a to the casing.

I claim:

1. The combination with a lock casing having an open side, a rotatable disk in said casing, the side of said disk facing said open side of the casing having a cam groove, and a shackle mounted on said casing; a bolt for locking said shackle, a lever for releasing said bolt, a spring connected to and carried by said lever and bolt for projecting the latter and yieldably holding said lever in inoperative position, a plate upon which said lever and bolt are both mounted, said plate, bolt and lever being insertible into said casing as a unit through the open side thereof and said lever having a lateral shoe then receivable in said cam groove, means for securing said plate in said casing, and a closure for said open side of the casing.

2. A permutation lock comprising a casing, a shackle extending into said casing, a bolt for locking said shackle, releasing means for said bolt having an operating shoe, and a rotatable disk in said casing for operating said releasing means, said disk having a relatively wide recess in one side extending from its center to its edge, the center line of said recess being disposed approximately on a radial line, said side of the disk also having inner, outer and intermediate cam grooves to receive said shoe, the full length of the inner groove and the greater part of the length of the other

- grooves being concentric with said disk, both ends of the inner and outer grooves and one end of said intermediate groove opening into opposite sides of said recess, the other end of 5 said intermediate groove opening into said outer groove, and the opposite end of said inner groove having a transfer groove opening into said intermediate groove, said inner groove and the inner end of said recess forming a truly circular track in which said 10 shoe travels idly when the disk is turned in one direction.
- In testimony whereof I have hereunto set my hand.

ELKANNAH S. PERRY.
